UNITED STATES PATENT OFFICE.

JOHN HERMAN, OF EASTON, PENNSYLVANIA.

DRAFTING OR MEASURING INSTRUMENT.

1,294,263.

Specification of Letters Patent. Patented Feb. 11, 1919.

Application filed October 24, 1918. Serial No. 259,466.

To all whom it may concern:

Be it known that I, JOHN HERMAN, a citizen of the United States, residing at Easton, in the county of Northampton and 5 State of Pennsylvania, have invented new and useful Improvements in Drafting or Measuring Instruments, of which the following is a specification.

This invention relates to drafting or measuring instruments or tools, and has for an 10 object to provide an improved tool of this character having a plurality of interchangeable leg extensions whereby said tool may be converted into and used as compasses, 15 dividers, calipers, or other instrument of similar type, said leg extensions and the means for attaching the same being of such a character that one extension or pair of extensions may be readily substituted for another, and that said extensions will be securely held in accurate position, these 20 results being accomplished by the use of parts of relatively simple and inexpensive construction.

25 Another object of the invention is to provide, in an instrument of the character referred to, improved and simplified means for connecting and operating the parts whereby the instrument may be quickly and 30 conveniently adjusted and the parts thereof steadied and securely held in adjusted position when in use.

The foregoing and other objects of the invention, together with means whereby the 35 same may be carried into effect, will best be understood from the following description of one form or embodiment thereof illustrated in the accompanying drawings. It will be understood, however, that the particular construction described and shown 40 has been chosen for illustrative purposes merely, and that the invention, as defined by the claims hereunto appended, may be otherwise practised without departing from 45 the spirit and scope thereof.

In said drawings:

Figure 1 is a side elevation of the complete instrument.

Fig. 2 is a similar view, partly broken 50 away, showing different leg extensions in place.

Figs. 3, 4 and 5 are detail sectional views

on the lines 3-3, 4-4, and 5-5, respectively, Fig. 1.

Referring to Fig. 1, the instrument comprises a pair of pivotally connected leg members 10, a pair of leg extensions 11 carried by said leg members, and means, hereinafter described, whereby said leg members may be relatively adjusted about their pivot and 55 retained in adjusted position.

As herein shown, the leg members 10 are coaxially pivoted upon opposite sides of a disk or flat cylindrical block 12 (Figs. 2 and 3) having opposing projecting alined trunnions 13 which are received in openings in the hubs 14 of said leg members, said hubs being retained in place by suitable means, as by riveting or upsetting the outer ends of said trunnions to form heads 15. Preferably, and as shown in Fig. 5, the hubs of the respective leg members 10 are oppositely offset to engage opposite faces of the block or disk 12 while bringing said leg members 60 into substantially the same plane. 75

Adjacent their outer ends the leg members 10 are formed with sockets 16 (see Fig. 4) and with openings 17 extending therethrough from the bottoms of the sockets. Loosely received in said sockets are heads 18 80 having threaded stems 19 of less diameter than the openings 17 and disposed therein, said stems being fitted with knurled nuts 20 engaging the opposite faces of the leg members. The heads 18 are provided with 85 transverse perforations to receive the shanks 21 of the leg extensions.

Said leg extensions may be of any suitable or desired form, and preferably a plurality of interchangeable sets are provided for 90 each instrument. In Fig. 1 is shown a pair of extensions 11 of suitable shape to adapt the instrument for use as a pair of internal calipers, while in Fig. 2 is shown in full lines a pair of extensions 11^a constituting 95 external caliper jaws, and in dotted lines extensions 11^b adapted to convert the instrument into a pair of dividers. Obviously extensions capable of rendering the instrument operative as a pair of draftsman's 100 compasses or as any other drafting or measuring instrument of similar type might be provided.

The extreme ends of the shanks 21 are

bifurcated, as shown at 22, to engage studs 23 carried by the leg members 10 at points spaced from the sockets 16, whereby, when the shanks are passed through the perforations in the heads 18 and the ends thereof engaged with said studs, said shanks will overlap the leg members and will be accurately positioned with respect thereto, while by tightening the nuts 20 said shanks 10 will be securely clamped in position. It will be noted that the loose mounting of the clamping devices 18, 19 in the sockets 16, and particularly the looseness of the stems 19 in the openings 17, permits said clamping devices to adjust themselves to the requirements, so that any variations in workmanship in the several leg extensions of the set is automatically compensated for. It will also be observed that the leg extensions 20 may be easily and quickly attached, removed, or interchanged merely by tightening or loosening the nuts 20 and slipping the shanks 21 into or out of the perforations in the heads 18, the engagement of the bifurcated ends of said shanks serving automatically to effect the longitudinal as well as the angular positioning of the leg extensions without special attention on the part of the user, so that a change may be made in a minimum length of time and with a minimum amount of trouble or possibility of error.

The disk or block 12 is formed with a diametrically disposed threaded opening to receive an adjusting screw 24 provided at its outer end with a suitable operating knob or handle 25. At its inner end the screw 24 is swiveled in a second disk or block 26 having alined trunnions 27, similar to the trunnions 13, and upon which are pivoted the inner ends of toggle links 28 pivoted at their outer ends to the leg members 10. Preferably, and as herein shown, a pair of links 28 is employed to connect the block 26 with each of the leg members, the links of each pair being spaced from one another and pivoted respectively to opposite sides of the leg members and of the block, one link of each pair being mounted on one of the trunnions 27. The construction shown affords a very simple, inexpensive, and easily operated means whereby the leg members with their extensions may be relatively adjusted about their common pivotal axis, and the operation of which will be obvious without further description.

For the purpose of steadyng the leg members in their adjusted positions there is provided a bow spring 29 which surrounds and 60 incloses the block 26, extends between the links 28 of each pair, and is engaged at its ends in sockets 30 in the inner sides of the leg members 10, said spring serving in a measure to protect and house the adjust-

ing mechanism, and being itself protect- 65 ed against accidental dislodgment by the links 28.

As will be seen the invention provides a very simple, inexpensive, and conveniently operated instrument of the character described, wherein the necessity for extremely fine and accurate workmanship in manufacture is obviated, which nevertheless is reliable and accurate in use, which by a quick and simple manipulation can be 75 adapted to a variety of purposes, and which possesses many other advantages which will be readily recognized by those skilled in the art.

I claim:

1. In an instrument of the character described, in combination, a leg member, clamping means carried thereby adjacent the outer end thereof, a leg extension carried by and overlapping said leg member and engaged by said clamping means, and coöperating positioning means on said leg member and leg extension at the inner end of the latter.

2. In an instrument of the character described, in combination, a leg member, a leg extension carried by and overlapping said leg member, said leg extension having a bifurcated inner end, means for clamping said extension to said member, and a stud on said member engaged by the bifurcated end of said extension.

3. In an instrument of the character described, in combination, a leg member having a socket and an opening extending 100 therethrough from the bottom of said socket, a perforated head loosely received in said socket and having a threaded stem of less diameter than said opening disposed therein, a nut on said threaded stem beyond said leg 105 member, a plurality of interchangeable leg extensions each having a shank adapted to be received in the perforation of said head, and coöperating positioning means on said leg member and shanks.

4. In an instrument of the character described, in combination, a pair of pivotally connected leg members each having adjacent its outer end a socket and an opening extending therethrough from the bottom of said socket, a perforated head loosely received in each of said sockets and having a threaded stem of less diameter than the corresponding opening disposed therein, nuts on said stems beyond said leg members, a 110 plurality of pairs of interchangeable leg extensions each having a shank adapted to be received in the perforations in said heads, said shanks having bifurcated inner ends, and studs on said leg members spaced from 115 said sockets and engaged by the bifurcated end of said shanks when said leg extensions are in position.

5. In an instrument of the character described, in combination, a block, a pair of leg members pivoted to said block, a second block, an adjusting screw swiveled in one
5 of said blocks and in threaded engagement with the other, a pair of links connecting said second block with each of said leg members, the links of each pair being pivoted, respectively, to opposite sides of said
10 second block, and a bow spring extending

around said second block and between the links of each pair, said spring engaging at its ends said leg members to steady the same.

In testimony whereof I have hereunto set my hand in presence of two subscribing 15 witnesses.

JOHN HERMAN.
